FUSE-PLUG.

1,330,630.

Specification of Letters Patent. Patented Feb. 10, 1920.

Application filed May 29, 1918. Serial No. 237,256.

To all whom it may concern:

Be it known that I, GILBERT W. GOODRIDGE, a citizen of the United States of America, residing at Bridgeport, in the county of Fairfield and State of Connecticut, have invented certain new and useful Improvements in Fuse-Plugs, of which the following is a specification.

My invention relates to fuse plugs, and 10 the object of my invention is to provide a plug of improved construction, particularly with reference to the fuse strip and associated terminals and the securing means by 15 which the use of solder or other material for securing the fuse in position may be dispensed with. Other features of improvement will also appear from the following description and from the accompanying drawing, in which—

20 Figure 1 is a broken plan of a fuse plug in which my invention is embodied in one form;

Fig. 2 is a broken side elevation thereof;

25 Fig. 3 is a vertical section on the line 3—3, Fig. 2;

Fig. 4 is a perspective of the fuse strip, detached;

30 Fig. 5 is a broken side elevation of a fuse plug body illustrating a modified fuse strip construction;

Fig. 6 is a perspective of one end of this modified fuse strip;

35 Figs. 7 and 8 are views corresponding to Figs. 5 and 6, showing a further modification;

Fig. 9 is a perspective of a wire fuse embodying my invention in modified form;

40 Fig. 10 is a bottom plan of a fuse plug in which my invention is embodied in any of the forms above referred to.

Referring to the construction shown in Figs. 1 to 4, the present fuse plug comprises an insulating body 20 of porcelain or the like, with fuse chamber 21, and exterior 45 thread 22 on which is screwed the shell contact 23 of the plug. At the entering end of the plug is a boss 24 and center contact 25. The fuse X extends from the center contact 25 through the fuse chamber to the screw 50 shell 23. The open end of the chamber 21 is closed by a disk 26 of mica, held in position by a cap 27, the top flange 28 of which overlies the disk 26, while its lower flange 29 is spun beneath the shoulder 30 at the head of 55 the porcelain and staked at 31 into a notch

32 formed in the shoulder 30. In these features the construction generally resembles the plug fuses now common on the market. In such plug fuses, however, it has been heretofore the common practice to secure the 60 fuse to the center and shell contacts by means of solder, and this has not only necessitated the use of a large quantity of solder (with the attendant expense), but has also resulted in the production of a fuse of 65 uncertain and varying capacity, since it is impossible in a practical manufacturing operation so accurately to regulate the amount of solder used at the two contacts as to preserve a precise length of fuse strip between 70 the points at which the solder is applied thereto. Moreover, it has been customary to add above the solder a plug of putty or the like, with the result that, on the blowing of the fuse, the vapors generated by the 75 melting of the solder and the putty have an explosive action which often shatters the plug with resulting danger to bystanders. This is particularly apt to be true in plugs sealed against the escape of the gases, al- 80 though for fire protection, it is highly desirable that the plugs should be so sealed. By the present construction I have eliminated the necessity for using solder, etc., in order to secure perfect contact between the 85 fuse ends and the contacts of the plug. Moreover, I have so constructed the fuse strip that its extent between the plug contacts is predetermined with exact accuracy, thus giving a uniform action for all plugs of 90 the same capacity. It has, furthermore, been found by repeated experiments that on the blowing of plugs of the present type, there is no resulting generation of explosive vapors and that the fuse strip melts at 95 its calibration point without injury to the plug as a whole or danger to bystanders or surrounding equipment.

In carrying out my invention, I have embodied it in a plug of the sealed or closed 100 type such as is shown in my previous Patent 923,642. As will be seen from Figs. 3 and 4, the center contact comprises a rivet 33, preferably of brass, the sealing head 34 of which is seated in a well 35 at the bottom 105 of the fuse chamber 21, while the outer end of the rivet pierces the boss 24 and is spread over the inner margins of the countersunk midportion of the center contact ring 25. Projecting inward from the head 34 are 110

flanges 36, between which one end of the zinc fuse strip X is received and held by tit rivets 37. The opposite end of the fuse strip X is secured in any suitable way to a terminal 38, the fuse end of which is preferably provided with a flange 39 adapted to embrace the fuse strip, so that the latter is engaged on both sides by the terminal 38 to which it is secured by crimping the engaged areas, as at 40, and by one or more tit rivets 41. Between the two terminal pieces 33 and 38, the strip is calibrated in any suitable way, as by a punching 42. The fuse strip thus prepared is mounted in the porcelain body 20 by inserting the terminal rivet 33 and spreading its free end into engagement with the center contact ring 25. The contact piece 38 is then passed over the barrier 43 which separates the chamber 21 from the well 44, and is drawn down into this well by any suitable appliance such as a hook engaging a perforation 45 formed in the end of the terminal 38. The well 44 opens at its lower end through the wall of the body 20 within the area of the threads 22. The end of the terminal 38, having been passed down through the well 44, is turned upward over the threads 22 formed in the porcelain and slightly offset against the shoulder 46 at the head of the plug. When the shell 23 is screwed into position, its upper end engages the terminal 38 and not only creases the latter into the spaces between the threads 22 in the porcelain, but also engages, with its upper edge, the offset end of the terminal and thus establishes good electrical connection therewith. After the shell 23 has been screwed home and bottomed against the shoulder 46, it is held in this position by staking its lower flange 47 into recesses 48 in the porcelain at several points indicated at 49 in Fig. 10. There is thus no danger of the shell backing off and making poor contact with the terminals 38 of the fuse strip. After the fuse has been thus inserted, the fuse chamber is closed by placing in position the mica disk 26 and applying the cap 27.

In the modification illustrated in Figs. 5 and 6, I have shown the same construction, except that the terminal of the fuse X is provided with flanges 50, thus affording a more extended bearing surface to be engaged by the screw shell 23. In order to insert this modified form of terminal into the well, the flanges 50 may be bent over as indicated by the dotted lines 51.

In Figs. 7 and 8 a further modification is illustrated, in that the terminal 38 instead of being carried up to the shoulder 46, is carried beneath the shoulder 52 at the entering end of the plug and is engaged by the lower flange 47 of the screw shell. It is, of course, immaterial whether the engagement between the terminal 38 and the screw shell 23 be made at the shoulder 46 or 52, depending pri-

marily upon the point at which it is proposed to bottom the screw shell in its home position.

In Fig. 9 the construction of the fuse strip is substantially the same as that shown in Fig. 4, with the exception that the fuse here comprises a thin wire of low capacity. At one end it is inserted in a tubular boss 54 extending from the inner face of the rivet head 34, and this extension is smashed down upon the end of the fuse wire by a press which simultaneously forms a clamping tit rivet 55. The opposite end of the fuse wire is inserted between the body of the terminal 38 and its flange 39, and is held against escape by crimping as in the case of the fuse strip X.

It will be seen that in these several constructions, not only is the fuse strip efficiently connected to its terminal pieces, but its length between the terminals is accurately predetermined, and the terminals themselves electrically and mechanically connected to the plug contacts without the use of solder or other foreign element. At the same time, the plug is maintained closed against the escape of flame on the blowing of the fuse, and inasmuch as the terminals 38 and 34 are of brass, there is no danger of their melting and soldering the plug into its receptacle. As the fuse strip is secured to the terminal pieces by machine, this operation is not only readily accomplished, but also the expense of manufacture is maintained low, and the assembly of the fuse in the plug is much more rapid than heretofore where solder has been used to connect it to the plug contacts.

Various modifications in the form of the terminals and in the manner of fastening to the screw shell and center contact will readily occur to those skilled in the art which do not depart from what I claim as my invention.

I claim:

1. A fuse plug having an insulating body externally threaded at its entering end and internally chambered to accommodate a fuse, said body being recessed to afford a lateral well opening from the fuse chamber to the exterior of the plug, in combination with a high resistance fuse having at one end a flexible, low-resistance terminal strap permanently clamped thereto and passing through said well to the exterior of the plug body, together with a shell contact screwing on the threads of the insulating body of the plug and mechanically and electrically engaging the projecting end of said fuse terminal strap.

2. A fuse plug having a chambered insulating body, a center contact at the entering end of the plug body and having a receiving terminal projecting inward into the chamber of said body, and a fuse ar-

ranged within said chamber and permanently clamped at one end to the receiving terminal of said center contact.

3. A fuse plug having an insulating body externally threaded at its entering end and internally chambered to accommodate a fuse, said body being recessed to afford a lateral well opening from the fuse chamber to the exterior of the plug, center and screw shell contacts on said plug, said center contact having a low-resistance terminal projecting inward into the chamber of said body, in combination with a high-resistance fuse having one end clamped to the terminal of said center contact and having a low-resistance flexible terminal strap clamped to its other end and projecting outward through the well in the plug body into mechanical and electrical engagement with the screw shell contact.

4. In a fuse, a fuse unit comprising a flexible high resistance fuse strap and low resistance readily deformable terminals permanently united thereto by interlocking offsets of both the fuse strap and terminal elements.

5. In a fuse plug, a fuse unit comprising a high-resistance fuse and independent low-resistance terminals clamped to its opposite ends, one of said terminals being readily deformable to accommodate itself to the threads of the plug.

6. A fuse plug having center and shell contacts and a fuse element connected solely by a permanent clamping engagement with said center and shell contacts of the plug.

7. In a fuse, a fuse unit comprising a flexible high resistance fuse strap and low resistance readily deformable terminals permanently united thereto by interlocking offsets of both the fuse strap and terminal elements, together with a fuse body of insulating material, and screw shell and center contact elements thereon directly connected to the fuse terminals solely by clamping engagement therewith, substantially as described.

8. In a fuse plug, a fuse unit comprising a high-resistance fuse element and independent low-resistance terminals permanently clamped to the opposite ends thereof, one of said terminals being a flexible strap adapted to be engaged by the shell contact of the plug.

9. In a fuse plug, a fuse unit comprising a high-resistance fuse element and low-resistance terminals permanently clamped to the opposite ends thereof, one of said terminals being a center contact rivet.

10. In a fuse plug, a fuse unit comprising a high-resistance fuse element and low-resistance terminals permanently clamped to the opposite ends thereof, one of said terminals being a flexible strap adapted to be engaged by the shell contact of the plug, and

the other of said terminals being a center contact rivet.

11. In a fuse plug, a fuse strip having at one end a terminal comprising a strap having a lateral flange folded across the end of the fuse strip and between which and the body of the strap the end of the fuse is permanently confined and readily clamped.

12. In a fuse plug, a fuse strip having at one end a shell terminal comprising a flexible strap having a flange between which and the body of the strap the end of the fuse is permanently confined and readily clamped.

13. In a fuse plug, a chambered insulating body exteriorly shouldered and threaded at its entering end and recessed to afford a passage opening from the interior to said threaded area, a shell contact screwing on said threaded area and abutting against said exterior shoulder; in combination with a high-resistance fuse having permanently secured thereto at one end an independent flexible low-resistance terminal passing out through said well and engaged between said screw shell and shoulder.

14. In a fuse plug, a chambered insulating body exteriorly shouldered and threaded at its entering end and recessed to afford a passage opening from the interior to said threaded area, a shell contact screwing on said threaded area and abutting against said exterior shoulder, in combination with a high-resistance fuse having permanently secured thereto at one end an independent flexible low-resistance terminal passing out through said well and overlying certain of the threads on the exterior of the plug body against which it is clamped by the screw shell.

15. In a fuse plug, a chambered insulating body exteriorly shouldered at its outer or head end, threads formed on said body between said head and the inner or entering end of the plug, said body being recessed to afford a passage opening from the interior to the exterior thereof between said shoulder and the entering end of the plug, a shell contact screwing on said threaded area and abutting against said shoulder in combination with a high resistance fuse having permanently secured thereto at one end a flexible low resistance terminal passing out through said passage and engaged between said shoulder and the abutting end of the screw shell.

16. In a plug fuse, a high resistance fuse element and imperforate low resistance terminals secured by interengaged offsets to the opposite ends thereof at predetermined points to insure an exact length of said fuse element between said terminals.

17. In a plug fuse, a high resistance fuse element and low resistance terminals secured to the opposite ends thereof at predeter-

mined points to insure an exact length of said fuse element between said terminals, one of said terminals constituting a center contact rivet.

18. In a plug fuse, a high resistance fuse element and low resistance terminals secured to the opposite ends thereof at predetermined points to insure an exact length of said fuse element between said terminals, one of said terminals constituting an independent low resistance strap mechanically and electrically connected to said fuse and readily deformable into undulations by the pressure of a screw shell terminal on the plug.

19. In a non-refillable fuse, a chambered insulating body, a screw shell side contact, a center contact plate, a fuse element, a center contact rivet secured to one end thereof and holding said center contact plate rigidly in position, a low resistance terminal secured to the opposite end of said fuse ele-

ment a predetermined distance from the center contact rivet, the said terminal being engaged and confined by the screw shell 25 contact of the plug.

20. A fuse comprising a chambered insulating body, a cap permanently secured in position on said body to close said chamber, an exterior screw shell threaded on said body at its entering end and permanently fixed in position, a low resistance center contact element at the entering end of the fuse body, in combination with a high resistance fuse arranged within the chamber of said body, and having one end permanently secured to the low resistance center contact element, and its other end permanently secured to a low resistance flexible strap clamped between the shell contact and the 40 body of the plug, substantially as described.

In testimony whereof I have signed my name to this specification.

GILBERT W. GOODRIDGE.
